UNITED STATES PATENT OFFICE.

ARTHUR GRANDJEAN, OF CINCINNATI, OHIO.

WATCH-CASE SPRING.

SPECIFICATION forming part of Letters Patent No. 311,894, dated February 10, 1885.

Application filed August 25, 1884. (No model.)

To all whom it may concern:

Be it known that I, ARTHUR GRANDJEAN, a citizen of the United States, and a resident of Cincinnati, in the county of Hamilton and State of Ohio, have invented a new and useful Watch-Case Spring, of which the following is a specification.

My invention relates to the springs of a watch-case, and which are known as "catch" and "lift" springs; and it consists of the construction in common of the catch-spring which locks the cover, and of the lift-spring which throws the cover back when it is relieved by the catch-spring.

The object of my invention is to produce a spring embodying both a catch and a lift spring for a watch-case in common, and which shall be superior to the springs previously devised in simplicity of construction and facility of placing in and removing from the case, and in cheapness of construction, and, above all, which shall not be liable to breakage.

Figure 1 is a side view showing the continuous side and the catch 2, and the lift-hook 3 diametrically opposite. Fig. 2 is a plan of the spring shown in position in the spring-chamber, which is indicated by the dotted lines 9 and 10. Fig. 3 is a view of the side opposite the one shown in Fig. 1, and shows 30 a break in the continuity of the spring. Fig. 4 is a front view.

The same letters or numbers indicate the same parts in all of the figures.

The spring consists of a continuous piece of 35 spring metal bent into a slightly-elliptical form, as shown in Fig. 2, and has a suture-joint at the middle of one side, as shown in Figs. 2 and 3. The catch 2 for locking the cover and the hook 3 for lifting the same are 40 placed diametrically opposite each other, the catch being at the front and the hook at the back of the spring.

From an inspection of the figures it will be seen that the greatest depths and cross-sections 45 of the spring-body 1 are at the front where the catch is located, at the middle of the continuous side, and at the middle of the opposite side where the joint is located. The catch 2 is of the usual construction, and is an up-

ward projection in common with the body of 50 the spring at its front. A hole, 4, is made through the spring-front directly beneath the catch 2 for the stem or the key-pipe, as usual, when the spring is used in a stem-winder. The front part of the spring tapers off gradually and symmetrically from each side of the catch to near the middle of the sides, where its branches similarly increase in depth until they merge into the middle portions, 5 and 6, which have the same depth as the section at 60 the catch, the top edge of the spring, however, being in the same plane throughout its entire length. Each side of the spring beyond the middles 5 and 6 of the sides tapers off gradually and symmetrically until a uniform section 65 is attained at the lift-hook. The lift-hook 3 projects upward from and is in common with the central portion of the back of the spring. The hook 3 projects upward and curves outward, and slightly tapers toward 70 the extremity. Where the spring metal is very rigid the sections of the tapered portions of the spring on each side of the hook 3 may be further gradually reduced to less sections than that at the hook. The joint at the middle of the side 6 of the spring consists of a gap, 7, cut into the end of one branch, and of a tongue, 8, formed on the end of the other branch, of a size and shape adapted to slip 75 into the gap 7. The tongue 8 is formed by cutting out a gap at each corner of the end and leaving a central part intact, so that there is a shoulder on each side of the tongue. The tongue is bent inward, and when the spring is in place in the case-center, as shown in Fig. 80 2, and the catch and lift-hook are properly adjusted, the spring is under pressure toward the center along the diameter through the catch and the lift-hook, and consequently the tongue 8 is maintained engaged within the gap 7, so that the spring, when in place and adjustment, acts as an unbroken hoop-spring. The spring is maintained in position within the spring-chamber by the engagement of the catch at the front and the lift-hook at the 85 back. There need be no pressure laterally against the walls of the spring-chamber either when idle or when in action, and since there

is no possibility of a tested spring so constructed ever breaking by use this spring could be used in a watch-case not having any protecting ring or wall between the movement 5 and the spring. When the spring is idle there is no pressure parallel to the depth of the spring against the interior of the center, or the top or the bottom of the spring-chamber. The spring, then, is to be considered as a 10 slightly-elliptical hoop suspended within the spring-chamber from the catch and the lift-hook, and as free to move throughout its circumference by flexure whenever compressed at either the catch or the lift-hook. For example, when the catch is pressed inward, the 15 hook becomes the stationary point, and as the long diameter of the ellipse is diminished the elliptical circumference is subjected to flexure throughout its extent and approaches a circular form. The key passes through the hole 4 beneath the catch and the shoulder on the stem, or the end of the key-pipe abuts against the exterior of the spring, and thus by pressing the crown inward the front of 20 the spring is pressed inward also, and carries the catch with it. The action of the spring, then, when the catch is pushed inward, is like that of a hoop secured at one point and pressed inward at the point diametrically opposite, and the flexure is all in 25 the same plane, so that there is no rubbing or friction on the walls of the spring-chamber or upon the ring surrounding the movement where such ring is used. The flexure of the 30 spring will be greatest of course at the reduced sections. The action of the spring when the cover acts upon the lift-hook is somewhat different. When the cover is thrown back, the extremity of the lift-hook is in contact with 35 the edge of the cover contiguous to the hinge, and the upper even edge of the spring is parallel with the adjacent top wall of the spring-chamber. The action upon the spring when the cover is first moved forward in closing it 40 is the same as when the catch is pressed inward; but when the cover is further closed the back portion of the spring, in addition to being bent inward, is bent downward until the lower edges of the deep sections intermediate 45 between the catch and the lift-hook come into contact with and press down upon the bottom of the spring-chamber, when further downward flexure takes place from these points back to the lift-hook. The slender portions of the 50 spring on each side of the lift-hook permit of gentle and uniform flexure, and are free to bend inward and downward without coming in contact with the walls of the spring-chamber. When the cover is released by the catch 55 2, the spring, being under pressure, reacts upon the cover and throws it back. As has been seen, the tapered or diminished portions of the spring are gradually reduced in cross-section, and are of considerable length and symmetrically disposed, while there is freedom of action 60 and provision for flexion throughout the

whole spring. Consequently this spring, when properly made, tested, and adjusted, cannot possibly break.

The spring is to be made of flat metal and stamped or cut out by machinery into the approximate form which the spring shown in the figures would have if unrolled or flattened out. The catch and the lift-hook and the parts of the joint 7 8 are then to be properly shaped, and, if necessary, the surface of the spring may be smoothed off. The spring is then to be bent into the elliptical or circular form shown, the joint made to work properly, and then the spring is to be tempered. 80

Many of the disadvantages of various catch and lift springs previously devised are given in a patent to W. H. Fitz Gerald and G. C. Smith, April 22, 1884, No. 297,123. Nosuch defects exist in my improved hoop-spring. 85 My spring is easily placed and adjusted within the spring-chamber of a case.

In placing my spring in a center opening centrally the front part is first inserted into the spring-chamber and the catch slipped into 90 its notch. The forefinger is then applied to the middle of the continuous side, and this side is pressed inward until the lift-hook catches in its notch. The end beyond the lift-hook will then spring into place, and by 95 pressing the thumb-nail against the end it will engage and lock with the tongue on the other end, and will then be in adjustment.

To remove the spring, the end having the tongue is pressed back or radially outward 100 from the center of the case, when the end having the gap is released and springs inward far enough to be grasped between the thumb and forefinger, and hence easily removed.

I claim—

1. A watch-case spring consisting of a hoop having its ends joined together at a point between the catch and the lift-hook, and having in common therewith a catch for locking the case-cover and a lift-hook for engaging with the hinge of the cover. 105

2. A watch-case spring consisting of a hoop made continuous by means of a joint located in the middle portion of one side and between the catch and the lift-hook, and having a hole 110 adjacent the catch for the stem or key-pipe, and having the body of the spring on each side of the catch reduced in cross-section, while the middle portions of each side of the spring have a depth corresponding to that at 115 the catch, and the sides beyond the middle tapered off to a uniform section at and near the lift-hook.

3. A watch-case spring consisting of a hoop made continuous by means of a joint located 120 in the middle portion of one side and between the catch and the lift-hook, and having a hole adjacent the catch for the stem or key-pipe, and having the body of the spring on each side of the catch reduced in cross-section, 125 while the middle portions of each side of the spring have a depth corresponding to that 130

at the catch, and the sides beyond the middle tapered off to a uniform section at and near the lift-hook, and the joint consisting of a gap in the end of one extremity of the spring, and 5 of a tongue at the other extremity, to interlock within the said gap and unite the said extremities of the hoop, whereby the hoop

may be made continuous and its action be made the same as if both sides of the hoop were solid.

ARTHUR GRANDJEAN.
